BOBBIN CONVEYER FOR WINDING
MACHINESJohn O. McKean, Westfield, Mass., assignor to
Foster Machine Company, Westfield, Mass., a
corporation of Massachusetts

Application March 22, 1933, Serial No. 662,012

5 Claims. (Cl. 198—73)

One object of my invention is to provide a means for receiving empty bobbins after they have been unwound on a winding machine and for transporting said bobbins to a certain predetermined point. A second object of my invention is to elevate such bobbins and discharge them so that they may be gathered in relatively large quantities. Another object of my invention is to obviate the necessity of workmen reaching under winding machines while in operation in order to remove the empty bobbins, which procedure has proved to be dangerous. Another object is to provide a driving means for such a conveyer which is adapted automatically to disconnect itself should the ordinary progress of the conveying means be accidentally interrupted. It will be evident that many other important and more detailed advantages inhere in the structure described in this specification and especially in those parts of this machine which are covered by claims.

My invention comprises generally a conveyer operated by the source of power which operates the winding machines and situated underneath said winding machines, which carries such empty bobbins as may be thrown into it to one end of the winding machine, where it elevates such bobbins and deposits them beyond the end frame of the machine.

My invention more specifically comprises a conveyer chain operated from the source of power of the winding machine through a slip-drive, and running in a supporting track. Onto this conveyer chain, aprons guide the deposited bobbins and there they are carried to the end of the machine where the bobbins are deposited by gravity at a point elevated appreciably above the level on which they were deposited. Other portions of my invention will be hereinafter specifically described.

A practical embodiment of my invention is presented in the accompanying drawings in which

Fig. 1 represents a plan view of the delivery end of my conveyer, showing the winding machine supporting frame with the winding mechanism removed therefrom.

Fig. 2 is a longitudinal section taken through the delivery portion along the line II—II of Fig. 1 looking in the direction of the arrows.

Fig. 3 is a cross section taken along the line III—III of Fig. 2 looking in the direction of the arrows.

Fig. 4 is a cross section of the delivery end of my conveyer taken along the line IV—IV

of Fig. 2 looking in the direction of the arrows.

Fig. 5 is a medial longitudinal section of that end of my conveyer opposite the delivery end, taken in the same plane as is Fig. 2.

1 is one of the frames supporting a winding unit. 2 is a specially constructed end frame, being that which supports the terminus of my conveyer, and which, of course, also supports one end of a winding unit. 3 is a driving chain driven from the source of power which actuates the winding machines, said driving chain passing over a sprocket wheel 4 immovably associated by set screw 5 on an axle 6 which is journaled in the frame by well known means. Also immovably associated with axle 6 by means of set screw 7 is driving arm 8 at the outer end of which is placed a slip-drive 9 having a pivoted prong 10 which normally drives sprocket wheel 11 by engagement against one of the spokes of said wheel, said wheel 11 floating on axle 6. When the motion of said wheel 11 is arrested the pressure against the pin 10 is increased and eventually causes it to swing on its pivot, first extending the contractile spring 12 by means of the pin 13 unitary with pin 10 and perpendicular to the plane in which pin 10 is pivoted; then being snapped away from engagement with any of the spokes of wheel 11 by the subsequent contraction of spring 12. When wheel 11 is again free so that it may operate, the pin 10 is manually reset so as to engage one of the spokes of wheel 11, thereby actuating said wheel in a normal manner.

Partially encircling sprocket wheel 11 is conveyer chain 14 which is equipped with pushers 15. The upper section of said conveyer chain 14 is supported by channel 16 which is in turn supported by apron sections 17 which are mounted on the frames 1 by means of round headed bolts 18, which serve to assist in straightening out and positioning the bobbins as they are carried past. Said apron sections 17 are so shaped and constructed as to form, throughout the length of the winding machine, a V-shaped channel, with the conveyer chain taking the place of the angle of the V. The apron sections 19 in the last section of the winding machine, i. e., its delivery end, secured to the frame in a manner similar to apron sections 17, are specially shaped in a rising curve followed by a rising straight section as is indicated in Fig. 2. Where this upward curve begins, the aprons make a V-shaped channel of the same cross section as in other sections of the machine, gradually narrowing as it reaches the delivery end. Said

apron sections 19, are constructed with turned down ear portions 20 to give a finished appearance and to protect workers from coming into contact with the returning portion of the conveyer chain. At the rising curved juncture between apron sections 19, I have devised a special track 21 for the conveyer chain made of hardened steel thus avoiding undue wear at a point which would normally be subject to great friction. At the top of the inclined straight juncture of apron sections 19, I have provided a free pulley wheel 22 which is mounted on a shaft 23 carried by arms 24 projecting from the terminal frame 2. The conveyer chain is led around said pulley and past or in contact with another free pulley 25 mounted on a shaft supported in arms projecting from side frame 26 of the winding machine.

From thence the conveyer chain is led into a channel guide 27 forming a track supported by arms 28 depending from frame members 1. Said channel guide is adapted to support the links of said conveyer chain while permitting the pushers 15 to pass through out of contact with any support, thereby avoiding undue wear on said pushers 15. Said channel guide 27 is made to support the conveyer chain 14 to a point proximate to the driving wheel 11, as shown in Fig. 5.

Loosely attached to the frame 2 by means of leather thongs 29 are two wooden guides 30, the upper ends of which are spaced a relatively short distance apart while the lower ends are shaped as is shown in Fig. 4 and are held somewhat wider apart by means of leather thongs 31 attached to the ears 20 by bolts 32.

Attached across the upper portion of said wooden guides 30 by means of screws 33 is a plate 34, the lower end of which has a turned up portion 35.

Carried by projecting arms 24 is a U-shaped projecting frame 36 to the middle portion of which is pivoted an inclined delivery slide 37, for the empty bobbins, extending proximate to the free pulley 22 and having, next to the conveyer chain itself, a V-shaped notch 38 slightly wider than the small diameter of an ordinary bobbin. On shaft 23 are mounted two pulleys 39 over each of which passes a thong 40 attached on its outer end to the inclined bobbin slide 37 by an extension thereon 41 and attached at the other end to a counterbalance weight 42.

Extending from the frame section 2 is a curved bumper bar 43 which serves to protect the mechanism at the delivery end of the conveyer from damage due to such apparatus as may be used to collect or carry away the deposited empty bobbins.

60 Operation

Normally when the winding machines are being used the conveyer will be moved by its driving sprocket wheel. However, since the bobbin conveyer-elevator is liable to clog up with lint or other material or may conceivably become jammed in some way and since, in any machine around which human beings work it is extremely advisable to provide instantaneous means of arresting moving parts, I have provided the slip-drive, or safety latch heretofore described whereby when the load on the conveyer chain reaches a predetermined maximum, the conveyer-chain-driving sprocket is automatically disconnected from the source of power, and remains dis-

connected until manually reconnected by an operator who will have, in the meantime, determined and remedied the cause of the stoppage.

It will be noted that the point at which the greatest friction will be found is the curved 5 uprising portion. By driving my conveyer from the end opposite to this curved uprising portion, I materially reduce the strain on the conveyer chain at that point, thereby greatly lessening the friction from what it would be if 10 the conveyer drive were at the discharge end. Such friction as there is at this point is effectively resisted through my use of a special hardened steel track.

In conveying the empty bobbins horizontally 15 until the last section is reached, I have devised a plan of conveying which is peculiarly appropriate for winding machines, which are made in multiple units and which may comprise a various number of such units.

Suppose a group of empty bobbins is thrown onto the apron sections 17. They will tumble by gravity down over the conveyer chain 14, which will transport, with the assistance of its pushers, those empty bobbins which lie longitudinally 25 over it, to the terminal section, where such longitudinally lying empty bobbins are elevated and deposited upon the bobbin slide for delivery into a suitable receptacle.

In case a bobbin does not first roll longitudinally onto the conveyer chain, it will be so agitated by the pushers, and by the round headed bolts which attach the apron to the frame, that they will eventually come to lie longitudinally on the conveyer chain.

It may happen that quite a number of empty bobbins will pile up in the terminal section waiting to be elevated by the pushers. In this case they gradually push the guides 30 outward toward the ears 20. Since this pushing tends 40 to oppose gravity, there is always a force tending to place the empty bobbins in the middle of the terminal apron sections where they can be engaged by the pushers.

The plate 34, 35 tends to prevent bobbins from 45 interfering with other portions of the machine and tends to facilitate their orderly elevation.

As the bobbins, one or more at a time, are delivered when the conveyer chain turns about pulley 22, they are dropped onto the bobbin slide 50 where they slide off into a waiting receptacle. In case a bobbin should become jammed between the bobbin slide and said pulley, the inner end of the bobbin slide is readily forced downward as shown in dotted lines on Fig. 2, permitting the 55 bobbin to fall clear of the machine.

The bumper extending near the bottom of the machine protects the delivery mechanism and the other winding machine mechanism from 60 injury through careless handling of the truck or receptacle onto which the bobbins fall.

It is evident that various changes may be made in the construction, form, and arrangement of the several parts without departing from the 65 spirit and scope of my invention, hence I do not intend to limit myself to the particular embodiment herein shown and described, but

What I claim is:

1. An empty bobbin conveyor for winding machines, means for actuating said conveyer and means for delivering the bobbins from said conveyer, comprising a bobbin slide pivoted at its delivery end, a counterbalance, a pulley, and a flexible member passing over said pulley con-

- necting said counterbalance with said bobbin slide.
- 5 2. An empty bobbin elevating conveyor for winding machines, aprons for guiding the bobbins onto said conveyer, guides for holding the bobbins proximate to the elevating portion of said conveyer and a stabilized delivery chute for the empty bobbins freely hinged at its delivery end.
- 10 3. An empty bobbin conveyor for winding machines including a horizontal portion and an elevating portion, inclined aprons for directing the empty bobbins onto said conveyer, yieldable guides sliding on said aprons adapted to press the bobbins toward said conveyer, and means for actuating said conveyer.
- 15 4. An empty bobbin conveyor for winding machines, means for actuating said conveyer, and

means for delivering the bobbins from said conveyer, said delivering means comprising a bobbin slide pivoted at its delivery end and having its free end extending proximate to the delivering end of said conveyer, a counterbalance, a pulley, and a flexible member passing over said pulley connecting said counterbalance with said free end of said bobbin slide.

5 5. A means for removing empty bobbins from a winding machine, said means including a conveyer adapted to transport the bobbins, means for directing the empty bobbins onto said conveyer, yieldable laterally-moving gravity-actuated guides adapted to press the bobbins toward 15 said conveyer, and means for actuating said conveyer.

JOHN O. McKEAN.
